MARINE TURBINE

Filed June 25, 1928

UNITED STATES PATENT OFFICE

ISIDRO GARCIA, OF BUENOS AIRES, ARGENTINA

MARINE TURBINE

Application filed June 25, 1928. Serial No. 288,004.

This invention relates to a new and useful device in the nature of a marine turbine control device especially adapted for use in power driven vessels, steamships and the like for the purpose of providing auxiliary power for steering.

The object of the invention is to provide turbines operated by the water through which the vessel is being propelled as a means of providing power for steering.

The device proposes to use water turbines connected for operation by water entering openings in the front of the ship due to the forward motion of the ship, and discharging the water from the rear of the ship. The turbines are connected with propellers arranged at the rear of the ship, preferably on opposite sides of the ship's propeller.

A further object of the invention is to provide a device of the class described of novel construction and arrangement of parts hereinafter more fully described, claimed and illustrated in the following description, appended claims and in the accompanying drawing.

Fig. 1 is a side elevational view of a ship constructed according to this invention.

Fig. 2 is a front end view thereof.

Fig. 3 is a fragmentary plan view of the turbines and connections therefrom.

Fig. 4 is a horizontal sectional view of one of the turbines.

Fig. 5 is a perspective view of the mechanism for moving certain of the bevel gears shown in Fig. 3, and also the valve control of one of the turbines.

In Fig. 1 of the accompanying drawing, I have shown a vessel 10, steamship or the like of the power driven type such as is usually propelled or driven through the water by means of a propeller 11, operatively connected to a suitable steam engine, steam turbine or the like, not shown on the drawing.

As here embodied my improved device comprises water turbines 11 of the centrifugal type. A shaft 12 is rotatively mounted in the housing of each of the turbines 11. A rotor 13 consisting of a plurality of radial blades is secured at its center or hub to the shaft 12. The housing is provided with a bottom

central opening 14, and a top opening 15, such as is the usual construction of a water turbine of the centrifugal type. The inlet element 16 is of tubular construction and is intercommunicative with the opening 15. An outlet element 17 is of tubular construction and is intercommunicative with the opening 14.

The turbine 11 is provided with a flanged element 18 or support as a means of attaching the turbine to the keel 19 of the vessel 10, or to any suitable portion thereof, in proximity to the lowermost inner portion of the hull of the said vessel. The inlet element 16 is provided with a flanged extremity 20 as a means of attaching the said inlet element to a similar flanged element 21 or extremity of the inlet member 22, of tubular construction which is suitably extended therefrom slightly below the water line 23 of the said vessel, openings 24 being formed or cut in the side of the said vessel 10 to accommodate the extended extremity of the said inlet members.

The outlet element 17 of the turbine is provided with a flanged extremity 24' as a means of attaching the said outlet element to a similar flanged extremity 25 of an outlet member 26, of tubular construction which is suitably extended therefrom to the rear of the hull of the vessel 10. Openings 27 are formed or cut in the hull 10 to accommodate the extended extremities of the said outlet members.

The above described construction is such as will permit the water through which the vessel 10 is propelled to enter through the opening 24 and pass thru the turbines 11 and rotate the rotors 13, and exhaust therefrom through the outlet members 26 and through the openings 27.

A hand wheel 28 is positioned within easy reach of the engineer or operator of the vessel 10, and is secured to the upper extremity of a shaft 29 rotatively mounted in brackets 30 and 31 secured to any suitable, convenient portion of the vessel 10. A bevel pinion 32 is secured to the lower extremity of the shaft 29 and meshes with a bevel gear 33 secured to a shaft 34 rotatively mounted in a bracket 35 secured to any convenient suitable portion of the vessel 10. A rack gear 36 is secured

to the extended extremity of the shaft 34 and meshes with racks 37 and 38 positioned respectively above and below the rack gear 36. The racks 37 and 38 are provided respectively with extended elements 39 and 40, slidably mounted in the brackets 41 and 42 secured to any suitable convenient portion of the vessel 10. Levers 43 and 44 are secured respectively to the extended elements 39 and 40 of the racks 37 and 38, and are extended therefrom and are provided with fork shaped extremities 45 and 46, respectively adapted to engage the bevel gears 47 and 48, respectively. The bevel gears 47 and 48 are slidably mounted on the shafts 49, which are provided with intermediate elements 50 and 51, of square transverse section, adapted to slidably accommodate similar shape central openings formed in the bevel gears 47 and 48. The shafts 49 are rotatively mounted in brackets 52 and 53 secured to any suitable convenient portion of the hull of the vessel 10.

Bevel pinions 54 and 55 are secured to shafts 56 and 57 rotatively mounted in brackets 58 and 59, and in suitable out board stuffing boxes 60 and 61 positioned at the rear of the hull of the vessel 10, at either sides of the above mentioned propeller 11. The shafts 56 and 57 are extended through the stuffing boxes 60 and 61, and have secured thereto at their extended extremities propellers 62 and 63, respectively.

The shafts 49 are provided with bevel gears 64 meshing with gears 65 on the shafts 12 of the turbines. Each of the inlets 22 is provided with a control valve 66 operated by handle 68 connected with link 67 slidably arranged and having vertical portions 69 provided with handles 70 pivotally connected so as to be swingable in a plane at right angles with the link 67, this connection being effected by the pintle pin 71.

A block 72 is fastened to some stationary part of the ship, and is formed with a plurality of vertical grooves 73 of engagement by the handle 70. A bar 74 urges the handle 70 into a groove 73 by virtue of being urged itself rearwards of springs 75.

Normally the gears 47 and 48 are disengaged from the gears 54 and 55, and the valves 66 are closed. The operation of the device consists in first turning the wheel 28 for moving the gears 47 and 48 into engagement with gears 54 and 55. Then if the ship is to be steered to the right, the propeller 62 must be set into operation. This is done by manually drawing the handle 70 free from its engaged groove 73, then moving the handle 70 for operating handle 68 to open the valve 66 which controls the turbines 11 connected to drive the propeller 62. Then the handle 70 is automatically reengaged in a groove 73 to hold its new position. For steering the ship to the left, the turbine connected with the propeller 63 is set into action.

While I have shown and described the preferred embodiment of my invention, it is to be understood that I do not limit myself to the precise construction herein disclosed and the right is reserved to all changes and modifications coming within the scope of the invention as defined in the appended claims.

Having thus described my invention what I claim as new and desire to secure by United States Letters Patent is:

1. In a device of the class described having a pair of propellers on opposite sides of the rear of a ship, gears connected for driving the propellers, other gears arranged to mesh or to move out of mesh with the said gears and mounted on shafts connected with water turbines, a means for manually simultaneously moving the second mentioned gears to the said positions, valves for controlling the water turbines, and means for manipulating and locking the valves.

2. In a device of the class described having a pair of propellers on opposite sides of the rear of a ship, gears connected for driving the propellers, other gears arranged to mesh or to move out of mesh with the said gears and mounted on shafts connected with water turbines, a means for manually simultaneously moving the second mentioned gears to the said positions, valves for controlling the water turbines, and means for manipulating and locking the valves, comprising levers connected with the valves, and means for holding the levers in adjusted positions.

In testimony whereof I have affixed my signature.

ISIDRO GARCIA.
